UNITED STATES PATENT OFFICE.

WILLARD T. SEARS, OF MONTCLAIR, NEW JERSEY, ASSIGNOR TO NILES-BEMENT-POND COMPANY, OF NEW YORK, N. Y., A CORPORATION OF NEW JERSEY.

SHAPING MACHINE.

1,423,266.

Specification of Letters Patent. Patented July 18, 1922.

Application filed May 22, 1919. Serial No. 298,924.

To all whom it may concern:

Be it known that I, WILLARD T. SEARS, a citizen of the United States, residing at Montclair, in the county of Essex and State 5 of New Jersey, have invented certain new and useful Improvements in Shaping Machines, of which the following is a specification.

One of the objects of this invention is to 10 provide a shaping machine which is capable of cutting in any one of four directions, as may be desired. Another object of the invention is to provide an improved electric drive mechanism for shaping or similar machines. Still another object of the invention 15 is to provide an improved feed mechanism for shaping machines including an independent electric motor. Still further objects of the invention will be apparent from 20 the following specification and claims.

In the accompanying drawings I have shown one embodiment of the invention, the drawings being to some extent diagrammatic. It will be understood that the drawings 25 are for illustrative purposes only and are not to be construed as defining or limiting the scope of the invention, the accompanying claims being relied upon for that purpose.

30 Of the drawings:

Fig. 1 is a vertical transverse sectional view taken along the lines 1—1 of Figs. 2 and 3.

Fig. 2 is a front view.

35 Fig. 3 is a plan view.

Fig. 4 is a diagram of electrical connections.

Referring to the drawings, 1 represents 40 the main frame or bed which carries the other parts. Carried by the bed 1 is a work table 2, this table, as shown, being mounted on an intermediate saddle plate 3. The work table is vertically adjustable on the saddle plate and can be locked in position 45 by means of bolts entering T-slots 4, 4. The saddle plate is preferably longitudinally adjustable along the bed, being held by bolts entering longitudinal T-slots 5, 5. For 50 moving the saddle plate there is preferably a pinion 6 engaging a longitudinal rack 7 on the bed.

There is provided a tool holder 8 which is adapted to be held and reciprocated by suitable devices carried by the bed 1. As illustrated, there is a saddle 9 which is longitudinally reciprocable along ways formed on the top of the bed. The saddle 9 is provided with transverse ways which support a transversely reciprocable head 10, this head carrying the aforesaid tool holder 8. The tool 60 holder 8 is adjustable or movable with respect to the head 10 so as to be capable of occupying any one of four operative positions at right angles to each other. The tool holder comprises a clapper plate 11 65 which is horizontally pivoted to the body of the tool holder and which carries the cutting tool. As illustrated, the body of the tool holder is cylindrical and fits a vertical cylindrical bearing 12 in the reciprocating head. 70 For turning the tool holder there is provided a worm 13 engaging a worm wheel 14 secured to the holder. With the tool holder adjustable, as shown, it will be seen that the tool can cut on either the outward stroke 75 or the inward stroke when the head 10 is reciprocated, and can cut on either the right-hand stroke or the left-hand stroke when the saddle 9 is reciprocated.

I provide mechanism for reciprocating 80 either the saddle or the head and, as preferred, this mechanism is constructed as follows: Rotatably mounted in suitable bearings in the bed is a longitudinal screw 15. Fitting this screw is a nut 16 secured to 85 the saddle. It will be seen that when the screw is turned the saddle is moved longitudinally along the bed. Also rotatably mounted in bearings in the bed is a longitudinal shaft 17 to which is splined a pinion 90 18. This pinion meshes with a rack 19 on the under side of the head 10. The pinion 18 is mounted to move longitudinally with the saddle, thus remaining at all times in engagement with the rack 19. It will be 95 seen that when the shaft 17 is turned the head 10 is moved transversely.

For supplying power to rotate the screw 15 or the shaft 17, there is preferably provided an electric motor 20. This motor is 100 connected through suitable speed-reducing gearing 21 with a short drive shaft 22

mounted in alinement with the shaft 17. Splined on the shaft 22 is a driving clutch element 23. This driving clutch element is adapted to engage a clutch element 24 secured to the shaft 17 or a clutch element 25 secured to a gear 26 loosely mounted on the shaft 22. The gear 26 meshes with a gear 27 on the rotatable screw 15. It will be seen that when the clutch element 23 is in engagement with the element 24 the shaft 17 is rotated, thus moving the head 10 transversely. When the clutch element 23 is in engagement with the element 25 the screw 15 is rotated, thus moving the saddle 9 longitudinally. The ratio between the gears 26 and 27 is preferably so related to the pitch of the screw 15 and to the size of the gear 18 that the head and the saddle are given approximately the same amount of movement for a given amount of movement of the shaft 22.

For reversing the rotation of the shaft 17 or of the screw 15 in order to reciprocate the head 10 or the saddle 9, I preferably provide means for automatically reversing the motor 20. As illustrated, there is a pilot switch 28 carried by the saddle 9, this switch having an arm which is adapted to be engaged by dogs 29, 29^a adjustably secured to the head 10. At the ends of the head movements these dogs alternately engage the operating arm of the switch 28 and serve to reverse the motor 20 in the way to be described. Also mounted on the saddle 9 is a switch 30 similar to the switch 28 and provided with a similar operating arm. Dogs 31, 31^a are adjustably secured to the bed 1. At the ends of the saddle movement these dogs alternately engage the operating arm of the switch 30 and serve to reverse the motor 20 in the way to be described.

The diagram of electrical connections in Fig. 4 is a simplified one, and it will be understood that certain auxiliary and ancillary features may be added as required, these features being well known in the electrical art. If the clutch element 23 is in its left-hand position, so that the motor serves to reciprocate the head 10, then the motor is under the control of the switch 28. For controlling the main circuit of the motor there are provided two operating solenoids 32 and 33 which respectively control switches 34 and 35 and 36 and 37. If the tool is set to cut on its outward stroke, as illustrated in Fig. 1, the switch 28 is moved toward the right (Figs. 1 and 4) to start the motor in the cutting direction. Such movement of the switch closes a circuit from the positive main through the contacts of the switch 28 and through the coil of the solenoid 32 back to the negative main. The solenoid 32 is energized and its core lifts, thus closing the switch 34 and opening the switch 35. With the switch 34 closed, a circuit extends from the positive main through the switch 34 to

the armature of the motor 20 and thence through the core of the solenoid 33 and the switch 37 back to the negative main. The motor then starts in the direction to move the head 10 outward. When the head 10 is moved outward to the desired extent, the dog 29^a engages the switch arm, thus moving the switch toward the left. This movement of the switch breaks the circuit for the solenoid 32 and thus causes a dynamic braking circuit through the motor armature. This braking circuit extends from the armature through the core of the solenoid 32 to the switch 35 and thence to the switch 37 and the core of the solenoid 33 and back to the motor armature.

The continued movement of the switch 28 toward the left serves to complete the circuit through the coil of the solenoid 33, this circuit extending from the positive main to the switch 28 and thence to the coil of the solenoid 33 and back to the negative main. When the switch 36 closes, a circuit extends from the positive main through the switch 36 to the armature of the motor 20 and thence through the core of the solenoid 32 and the switch 35 back to the negative main. The motor then starts in the direction to move the head 10 inward. When the head 10 is moved inward to the desired extent, the dog 29 engages the switch arm, thus moving the switch toward the right. This movement of the switch breaks the circuit for the solenoid 33 and thus again closes the dynamic braking circuit through the motor armature. Subsequently, the motor is started in the direction first described and these operations are repeated, the motor thus being repeatedly reversed and the head 10 thus being reciprocated.

In order that the tool may be moved relatively slowly in the cutting direction and relatively fast in the return direction, I provide adjustable resistances 38 and 39 which are adapted to be placed in circuit with the shunt field 40 of the motor. Associated respectively with the switches 34 and 36 and adapted respectively to be opened simultaneously with the closing thereof, are switches 41 and 42. By means of a manually movable switch 43 either of the switches 41 and 42 can be connected with the circuit of the shunt field so as to cut out the resistance 39. With the tool holder adjusted, as shown, for cutting in the outward direction, the switch 43 occupies its right-hand position (shown in Fig. 4) and during the cutting stroke only the resistance 38 is in circuit, thus providing a strong field and a slow motion. On the return stroke the switch 42 is open, thus placing both of the resistances 38 and 39 in the field circuit and providing a weaker field with a consequently higher speed. If the tool holder is reversed so as to cut in the inward direc-

tion, the switch 43 is moved to its left-hand position, thus providing a slow speed during the inward movement and a higher speed during the outward movement.

- 5 When the clutch element 23 is moved to the right so that the screw 15 is rotated to reciprocate the saddle, the operation is similar to that already described except that the motor is controlled by means of the switch 10 30 instead of the switch 28. The two switches 28 and 30 are connected in parallel and their operation is identical. It will be understood that the switch 43 is shifted to one position or the other in accordance with 15 the adjustment of the tool holder 8 in order to provide a slow speed in the cutting direction and a faster speed in the return direction.

Feed is effected by slowly or intermittently 20 rotating either the screw 15 or the shaft 17. For supplying power for this purpose, there is preferably provided an electric feed motor 44. This motor is connected through suitable speed-reducing gearing 45 with a 25 short shaft 46 mounted in alignment with the screw 15. Splined on the shaft 46 is a driving clutch element 47. This driving clutch element is adapted to engage the clutch element 48 secured to the screw 15, or 30 the element 49 secured to a gear 50 loosely mounted on the shaft 46. The gear 50 meshes with a gear 51 on the shaft 17. It will be seen that when the clutch element 47 is in engagement with the element 48 the 35 screw 15 is rotated, thus moving the saddle 9 longitudinally. When the clutch element 47 is in engagement with the element 49 the shaft 17 is rotated, thus moving the head 10 transversely. The ratio between the gears 40 50 and 51 is preferably so related to the pitch of the screw 15 and to the size of the gear 18 that the head and the saddle are given approximately the same amount of movement for a given amount of movement 45 of the shaft 46. Operating levers 52 and 53 are provided respectively for the clutch elements 23 and 47, and these levers are preferably connected together, as for instance by a link 54, so as to be operated simultaneously. For actuating the clutches there is 50 provided a hand lever 55. When the clutch element 23 is moved to connect the motor 20 with the shaft 17, the clutch element 47 is moved to connect the motor 44 with the 55 screw 15; and, conversely, when the clutch element 23 is moved to connect the motor 20 with the screw 15 the clutch element 47 is moved to connect the motor 44 with the shaft 17.

60 Preferably the feed motor 44 is reversed, being started first in one direction and then in the other at the ends of the movements of the head 10 or of the saddle 9, as the case may be. In order that the motor may move 65 the screw 15 or the shaft 17 in one direction

only notwithstanding the reversing of the motor, there is provided a reversible ratchet clutch 56. By reversing the action of this clutch, the power connection from the feed motor may be operative for either direction, 70 thus enabling either the screw 15 or the shaft 17 to be turned in either direction to effect feeding in either direction.

The electrical connections for starting the feed motor 44 in opposite directions at the 75 ends of the movements of the head or the saddle, are indicated in Fig. 4. If the head 10 is being reciprocated by the motor 20 the feed motor 44 is mechanically connected to feed the saddle 9 longitudinally as before 80 described and the pilot switch 28 is operative, as already stated. The switch 28 is provided with supplemental contacts 57 shown as located at the bottom, and when the switch is moved to its right-hand position a circuit is established from the positive main through the lower contacts 57 to a contact 58 of a limit switch 59. The limit switch 59 is preferably connected with the driving element of the reversible ratchet 85 clutch 56 and, when the switch is in the position shown in Fig. 4, a connection is made from the contact 58 to a contact 60. The circuit then extends from the contact 60 to the coil of a solenoid 61 and thence back to 90 the negative main. The energizing of the solenoid 61 closes a switch 62 and establishes a circuit from the positive main through the switches 34 and 62 to the armature of the motor 44. Then the circuit extends through the core of the solenoid 33 and the switch 37 back to the negative main. The feed motor then starts, moving the limit switch 59 and the driven element of the 95 ratchet clutch 56 in one direction, as for instance the clockwise direction indicated in 100 Fig. 4. The movement of the limit switch serves to disconnect the contacts 58 and 60 and serves to connect the contact 60 with a contact 63 similar to the contact 58. The 105 breaking of the connection between the contacts 58 and 60 causes the switch 62 to open, thus stopping the feed motor.

When the switch 28 is moved to its left-hand position, a circuit is again established 115 through the contacts 57, this circuit, however, extending through the contact 63 instead of through the contact 58. The switch 62 is closed as before and a circuit is established through the motor armature, this circuit extending from the positive main through the switch 36 to the armature, and thence through the switch 62 to the core of 120 the solenoid 32 and the switch 35 back to the negative main. The feed motor then 125 starts in the opposite direction, returning the limit switch 59 to the position shown in Fig. 4, with the contacts 58 and 60 connected. The disconnecting of the contacts 60 and 63 stops the motor as before. In the way de 130

scribed, the feed motor is given limited rotation at the beginning of each movement of the head.

If the saddle 9 is being reciprocated by the motor 20 the feed motor 44 is mechanically connected to feed the head 10 transversely as before described and the pilot switch 30 is operative as already stated. The operation of the feed motor is similar to that described except that it is controlled by means of contacts 64 on the switch 30. The motor is given limited rotation at the beginning of each movement of the saddle.

By means of the reversible ratchet clutch 56, the feed motor can be made to effect feeding in either direction. It will therefore be seen that when the head 10 is being reciprocated transversely a limited longitudinal feeding movement in either direction can be given to the saddle by turning the screw 15 by means of the feed motor, in the way described. Similarly, when the saddle is being reciprocated longitudinally, a limited transverse feeding movement in either direction can be given to the head by turning the shaft 17 by means of the feed motor, in the way described.

What I claim is:

1. The combination of a work table, a tool holder, an electric motor for causing relative reciprocation of such members either longitudinally or transversely, and means including automatic means for controlling the operation of the motor for causing the reciprocating motion of the reciprocating member in either direction to be relatively slow and in the opposite direction to be relatively fast.

2. The combination of a work table, a tool holder, an electric motor for causing relative reciprocation of such members either longitudinally or transversely, and switch means on the reciprocating member for automatically controlling the reciprocation in either direction.

3. The combination of a work table, a tool holder, an electric motor for causing relative reciprocation of such members either longitudinally or transversely, and two switches arranged in parallel for automatically controlling the transverse and longitudinal reciprocations respectively.

4. The combination of a work table, a tool holder, an electric motor for causing relative reciprocation of such members either longitudinally or transversely, and two switches on the reciprocating member arranged in parallel for automatically controlling the transverse and longitudinal reciprocations respectively.

5. The combination of a work table, a tool holder, an electric motor for causing relative reciprocation of such members either longitudinally or transversely, and two switches arranged in parallel and operated

by the reciprocating member for automatically controlling the transverse and longitudinal reciprocations respectively.

6. In a shaper, the combination of a work table, a tool holder, a supporting means therefor, means including a reversing electric motor for reciprocating the tool holder either longitudinally or transversely, means whereby the tool holder may be moved angularly with respect to its supporting means into any one of four cutting positions corresponding respectively to the two opposite longitudinal strokes and the two opposite transverse strokes, and means for automatically reversing the motor.

7. The combination of a work table, a tool holder, means including a reversing electric motor for effecting relative reciprocation between the table and the holder, and means for causing the rotation of the motor in either direction as desired to be relatively slow and in the opposite direction to be relatively fast.

8. The combination of a work table, a tool holder, means including a reversing electric motor for effecting relative reciprocation between the table and the holder, an automatic switch for reversing the motor, and means under the control of the switch for causing the rotation of the motor in either direction as desired to be relatively slow and in the opposite direction to be relatively fast.

9. The combination of a work table, a tool holder, means including a reversing electric motor for effecting relative reciprocation between the table and the holder, an electromagnetic controlling mechanism for the motor, an automatic switch for operating the controlling mechanism to reverse the motor, and means under the control of the controlling mechanism for causing the rotation of the motor in either direction as desired to be relatively slow and in the opposite direction to be relatively fast.

10. The combination of a work table, a tool holder, means including a reversing electric motor for effecting relative reciprocation between the table and the holder, an automatic switch for reversing the motor, resistance for the shunt field circuit of the motor, automatic means for placing the resistance in the said circuit during rotation of the motor in one direction and removing it from the circuit during rotation in the other direction, and means whereby the resistance may be placed in the circuit during the rotation of the motor in either direction.

11. In a shaper, the combination of a work table, a tool holder, means including a reversing electric motor for reciprocating the holder either longitudinally or transversely, means operative on the motor for causing the motion of the tool holder in either longitudinal direction or either transverse direc-

tion as desired to be relatively slow and in the opposite direction to be relatively fast, and means automatically reversing the motor.

5 12. In a shaper, the combination of a work table, a tool holder, means including a reversing electric motor for reciprocating the tool holder either longitudinally or transversely, two pilot switches for reversing the 10 motor one operative during longitudinal reciprocation and the other operative during transverse reciprocation, and means operative on the motor and controlled by the pilot switches for causing the motion of the head 15 or saddle in one direction to be relatively slow and in the opposite direction to be relatively fast.

13. In a shaper, the combination of a bed, a saddle longitudinally reciprocable along 20 the bed, a head transversely reciprocable on the saddle, a reversing electric motor, mechanism for optionally transmitting motion from the motor to reciprocate the saddle on the bed or to reciprocate the head on the 25 saddle, two pilot switches carried by the saddle and each adapted to reverse the motor, adjustable dogs on the head for operating one pilot switch, and adjustable dogs on the bed for operating the other pilot 30 switch.

14. The combination of a work table, a tool holder, and means for causing relative reciprocation of such members either longitudinally or transversely and for automatically 35 feeding one of the members transversely of either reciprocation, the said means including an automatically controlled electric motor adapted to perform one of the said movements in either of the said directions.

15. The combination of a work table, a tool holder, and means for causing relative reciprocation of such members either longitudinally or transversely and for automatically 45 feeding one of the members transversely of either reciprocation, the said means including an electric motor automatically controlled by the reciprocation and adapted to perform one of the said movements in either of the said directions.

16. The combination of a work table, a tool holder, means for causing relative reciprocation of such members either longitudinally or transversely and for automatically 55 feeding one of the members transversely of either reciprocation, the said means including an electric motor, and switch means on the reciprocating member for controlling the motor.

60 17. The combination of a work table, a tool holder, means for causing relative reciprocation of such members either longitudinally or transversely and for automatically 65 feeding one of the members transversely of either reciprocation, the said

means including an automatically controlled electric motor, and means for causing the reciprocating motion of the reciprocating member either longitudinally or transversely in one direction to be relatively slow and in 70 the opposite direction to be relatively fast.

18. In a shaper, the combination of a work table, a tool holder, means including a single reversing electric motor for optionally reciprocating the tool holder either longitudinally or transversely, a feed motor, and automatic means operative on the feed motor for feeding the tool holder either transversely or longitudinally perpendicularly to the reciprocation.

19. The combination of a work table, a tool holder, and an electric motor for automatically feeding one of such members in either of two relatively right angular directions.

20. The combination of a work table, a tool holder, and an electric motor for automatically and intermittently feeding one of such members in any one of four relatively right angular directions.

21. The combination of a work table, a tool holder, means for causing relative reciprocation of such members either longitudinally or transversely, and an electric motor for automatically and intermittently feeding 95 one of the members in a direction transversely of either reciprocation.

22. The combination of a work table, a tool holder, means for causing relative reciprocation of such members either longitudinally or transversely, and an electric motor controlled by the reciprocation for automatically and intermittently feeding one of the members in a direction transversely of either reciprocation.

23. The combination of a work table, a tool holder, means for causing relative reciprocation of such members either longitudinally or transversely, a reversing electric feed motor for feeding one of such members 110 in a direction transversely of the reciprocation, and switch means on the reciprocating member for controlling the operation of the motor.

24. The combination of a work table, a tool holder, two electric motors, one motor being adapted to cause relative reciprocation of such members either longitudinally or transversely and the other motor being adapted to feed one of the members transversely of the reciprocation, and automatic means for controlling the operation of the motors.

25. The combination of a work table, a tool holder, two electric motors, one motor 125 being adapted to cause relative reciprocation of such members either longitudinally or transversely and the other motor being adapted to automatically feed one of the members transversely of the reciprocation,

and mechanism including switch means controlled by the reciprocating member for automatically controlling the motors.

26. The combination of a work table, a 5 tool holder, two electric motors, one motor being adapted to cause relative reciprocation of such members either longitudinally or transversely and the other motor being adapted to automatically feed one of the 10 members transversely of the reciprocation, and mechanism including switch means on the reciprocating member for automatically controlling the motors.

27. The combination of a work table, a 15 tool holder, two electric motors, one motor being adapted to cause relative reciprocation of such members either longitudinally or transversely and the other motor being adapted to automatically feed one of the 20 members transversely of the reciprocation, and means including two switches on the reciprocating member for automatically controlling the motors.

28. The combination of a work table, a 25 tool holder, two electric motors, one motor being adapted to cause relative reciprocation of such members either longitudinally or transversely and the other motor being adapted to automatically feed one of the 30 members transversely of the reciprocation, and means including two switches for automatically controlling the relative reciprocation of the said members in the said two directions respectively and another switch connected to the first two switches for automatically controlling the feeding movements.

29. The combination of a work table, a tool holder, two electric motors, one motor being adapted to cause relative reciprocation 40 of such members either longitudinally or transversely and the other motor being adapted to automatically feed one of the members transversely of the reciprocation, and means including two switches arranged 45 in parallel for automatically controlling the relative reciprocation and another switch arranged in series with the first two switches for automatically controlling the feeding movements.

50. 30. The combination of a work table, a tool holder, two electric motors, one motor being adapted to cause relative reciprocation 55 of such members either longitudinally or transversely and the other motor being adapted to feed one of the members transversely of the reciprocation, and means including automatic means for controlling the 60 operation of the motors for causing the reciprocating motion of the reciprocating member either longitudinally or transversely in one direction to be relatively slow and in the opposite direction to be relatively fast.

31. The combination of a work table, a tool holder, two electric motors, one motor 65 being adapted to cause relative reciproca-

tion of such members either longitudinally or transversely and the other motor being adapted to feed one of the members transversely of the reciprocation, and means including automatic means for controlling the 70 operation of the motors for causing the reciprocating motion of the reciprocating member in either direction to be relatively slow and in the opposite direction to be relatively fast.

75 32. The combination of a work table, a tool holder, two electric motors, one motor being adapted to cause relative reciprocation of such members either longitudinally or transversely and the other motor being 80 adapted to feed one of such members in either direction transversely to the reciprocation, and automatic means for controlling the operation of the motors.

85 33. In a shaper, the combination of a work table, a tool holder, means including a reversing electric motor for reciprocating the tool holder either longitudinally or transversely, an electric motor for feeding the tool holder either transversely or longitudinally perpendicularly to the reciprocation, and automatic means for controlling the 90 operation of the motors.

95 34. In a shaper, the combination of a work table, a tool holder, means including a reversing electric motor for reciprocating the tool holder either longitudinally or transversely, an electric motor for feeding the tool holder in either direction either transversely or longitudinally perpendicularly to 100 the reciprocation, and automatic means for controlling the operation of the motors.

105 35. The combination of a work table, a tool holder, means including a reversing electric motor for effecting relative reciprocation between the table and the holder, means for causing the rotation of the motor in either direction as desired to be relatively slow and in the opposite direction to be relatively fast, an electric motor for feeding the tool holder either transversely or longitudinally perpendicularly to the reciprocation, and automatic means for controlling the 110 operation of the motors.

115 36. The combination of a work table, a tool holder, means including a reversing electric motor for effecting relative reciprocation between the table and the holder, means for causing the rotation of the motor in either direction as desired to be relatively 120 slow and in the opposite direction to be relatively fast, an electric motor for feeding the tool holder in either direction either transversely or longitudinally perpendicularly to the reciprocation, and automatic means for 125 controlling the operation of the motors.

37. In a shaper, the combination of a bed, a saddle longitudinally reciprocable along the bed, a head transversely reciprocable on the saddle, a reversing electric motor, mech- 130

anism for optionally transmitting motion from the motor to reciprocate the saddle on the bed or to reciprocate the head on the saddle, an electric feed motor, and mechanism for optionally transmitting motion from the feed motor to feed the head when the saddle is reciprocated or to feed the saddle when the head is reciprocated.

38. In a shaper, the combination of a bed, 10 a saddle longitudinally reciprocable along the bed, a head transversely reciprocable on the saddle, a rotatable longitudinal screw, a nut carried by the saddle and engaging the screw, a rotatable longitudinal shaft, a 15 pinion splined on the shaft and movable longitudinally with the saddle, a transverse rack on the head meshing with the pinion, a reversing electric motor, mechanism for optionally connecting the motor to the screw 20 to reciprocate the saddle or to the shaft to reciprocate the head, an electric feed motor, and mechanism for connecting the feed motor to the shaft when the main motor is connected to the screw and for connecting the 25 feed motor to the screw when the main motor is connected to the shaft.

39. In a shaper, the combination of a work 30 table, a tool holder, means including a reversing electric motor for reciprocating the tool holder either longitudinally or transversely, two pilot switches for reversing the motor one operative during longitudinal reciprocation and the other operative during transverse reciprocation, an electric motor 35 for feeding the tool holder either transversely or longitudinally perpendicularly to the reciprocation, and connections whereby either pilot switch serves to control the feed motor.

40. 40. In a shaper, the combination of a work 40 table, a tool holder, means including a reversing electric motor for reciprocating the tool holder either longitudinally or transversely, two pilot switches for reversing the motor one operative during longitudinal reciprocation and the other operative during transverse reciprocation, an electric motor 45 for feeding the tool holder either transversely or longitudinally perpendicularly to the reciprocation, connections whereby either pilot switch upon being moved serves to start the feed motor, and a supplemental switch for stopping the feed motor after movement to a predetermined extent.

55. 41. The combination of a work table, a tool holder, means for causing relative reciprocation of such members either longitudinally or transversely, an electric motor for automatically feeding one of the members 50 transversely of either reciprocation, and means for readily changing the directions of the reciprocating and feeding movements.

42. The combination of a work table, a tool holder, means for causing relative re-

ciprocation of such members either longitudinally or transversely, an electric motor for automatically feeding one of the members transversely of either reciprocation, and a single means for readily changing the directions of the reciprocating and feeding 65 movements. 70

43. The combination of a work table, a tool holder, an electric motor for causing relative reciprocation of such members either longitudinally or transversely, an electric 75 motor for automatically feeding one of the members transversely of either reciprocation, and mechanical means for changing the directions of the reciprocating and feeding movements. 80

44. The combination of a work table, a tool holder, an electric motor for causing relative reciprocation of such members either longitudinally or transversely, an electric 85 motor for automatically feeding one of the members transversely of either reciprocation, and clutch means for changing the directions of the reciprocating and feeding movements. 90

45. The combination of a work table, a tool holder, an electric motor for causing relative reciprocation of such members either longitudinally or transversely, an electric motor for automatically feeding one of the members transversely of either reciprocation, a pair of clutches operatively connected together, and a hand lever for operating such clutches to change the directions 95 of the reciprocating and feeding movements. 95

46. In a shaper, the combination of a work 100 table, a vertically extending tool holder, means for causing reciprocation of the tool holder either longitudinally or transversely, and means comprising a worm and worm wheel for moving the tool holder 105 about its vertical axis angularly with respect to its supporting means into any one of four cutting positions corresponding respectively to the two opposite longitudinal strokes and the two opposite transverse 110 strokes. 110

47. In a shaper, the combination of a work 115 table, a vertically extending tool holder, means for causing the reciprocation of the tool holder either longitudinally or transversely and for causing the motion in either transverse or longitudinal direction to be relatively slow and in the other direction to be relatively fast, and means comprising a worm and worm wheel for moving the tool 120 holder about its vertical axis angularly with respect to its supporting means into any one of four cutting positions corresponding respectively to the two opposite longitudinal strokes and the two opposite transverse 125 strokes. 125

48. In a shaper, the combination of a work table, a tool holder, means for causing the

reciprocation of the tool holder either longitudinally or transversely, means whereby the tool holder may be moved angularly with respect to its supporting means into any one of 5 four cutting positions corresponding respectively to the two opposite longitudinal strokes and the two opposite transverse

strokes, and means other than the reciprocating means for feeding the tool holder either transversely or longitudinally transversely of 10 the reciprocation.

In testimony whereof, I hereto affix my signature.

WILLARD T. SEARS.

Certificate of Correction.

It is hereby certified that in Letters Patent No. 1,423,266, granted July 18, 1922, upon the application of Willard T. Sears, of Montclair, New Jersey, for an improvement in "Shaping Machines," an error appears in the printed specification requiring correction as follows: Page 5, line 83, claim 19, before the word "feeding" insert the words *and intermittently*; and that the said Letters Patent should be read with this correction therein that the same may conform to the record of the case in the Patent Office.

Signed and sealed this 29th day of August, A. D., 1922.

[**SEAL.**]

KARL FENNING,

Acting Commissioner of Patents.
